UNITED STATES PATENT OFFICE.

NATHAN W. HENDRYX, OF NEW HAVEN, CONNECTICUT, ASSIGNOR TO THE ANDREW B. HENDRYX CO., OF NEW HAVEN, CONNECTICUT, A CORPORATION.

DESIGN FOR A BIRD-CAGE.

45,005.

Specification for Design.

Patented Dec. 9, 1913.

Application filed October 6, 1913. Serial No. 793,769. Term of patent 14 years.

To all whom it may concern:

Be it known that I, NATHAN W. HENDRYX, a citizen of the United States, residing at New Haven, in the county of New Haven and State of Connecticut, have invented a new, original, and ornamental Design for Bird-Cages, of which the following is a specification, reference being had to the accompanying drawing, forming part thereof.

The figure is a perspective view of a bird cage showing my new design.

I claim:

The ornamental design for a bird cage, as shown.

NATHAN W. HENDRYX.

Witnesses:

M. L. SHERMAN,

L. CARRINGTON.
